REMOTELY CONTROLLED TOY

John William Arpin, Montclair, N. J.

Application January 29, 1949, Serial No. 73,599

4 Claims. (Cl. 46—210)

1

This invention relates to toys and more particularly to a toy which may be steered and driven by remote control. In general, toys of this nature take the form of vehicles such as an automobile of which the wheels are steered by a solenoid arrangement or the like. Driving power is generally supplied by an electric motor which actuates the front or rear pair of wheels or their axles.

The present invention provides a toy which performs both steering and driving functions with a minimum of parts so as to render the toy less prone to mechanical disorders while effecting considerable manufacturing economies. It is most important in a toy of this type to reduce manufacturing costs so that the article can be produced and sold at a reasonable and attractive price. The instant invention substantially eliminates separate steering means in that the driving power itself is so arranged in combination with the wheel structure that the steering is automatically accomplished thereby. This is effected by pivoting of an axle upon which the wheels are freely rotatable. The driving power is applied to only one wheel and the pivoted nature of the axle permits it to swing pursuant to the driving power applied to said one wheel so that the car is driven with the axle in swung position. This constitutes steering the vehicle. As will be hereinafter explained, the vehicle may be effectively steered either to the right or to the left and reversal in a curved direction is also provided.

In a second preferred embodiment of the invention, the vehicle may be completely steered either to the left or to the right by means of a remote steering wheel which simulates that of a conventional automobile.

The invention will be further understood from the following description and drawings in which:

Fig. 1 is an elevational view of a toy vehicle and its remote controlling apparatus.

Fig. 2 is a bottom plan view thereof.

Fig. 3 is an internal plan view of the motor and driven wheels and illustrating the electrical connections.

Fig. 4 is an enlarged section along the lines 4—4 of Fig. 1.

Fig. 5 is an enlarged section along the lines 5—5 of Fig. 3.

Fig. 6 is a schematic view illustrating the course of a forwardly driven vehicle and including interruptions thereof.

Fig. 7 is a schematic view illustrating a modified embodiment.

In the form shown, the toy comprises an auto-

10 motive vehicle having a body 10 which simulates a conventional automobile. Body 10 may take the form of a hollow plastic member. The rear wheels 11 and 12 are freely rotatable on axle 13 which connects them. A pair of struts 14 and 15 may be molded integral with the vehicle body and terminate in yokes 16 and 17 into which the axle 13 may be snapped. This is conventional practice in connecting the rear wheels of a toy vehicle.

15 A bottom plate 18 supports the front wheels 19 and 20 as well as the electric motor 21. Plate 18 is connected to the vehicle as by resilient pins 18a which snap into suitable openings therethrough. Motor 21 and wheels 19 and 20 are assembled as a sub-unit which is pivoted as by a rivet 22 to the plate 18. Thus, the motor and front wheels turn in unison.

20 Motor 21 is of a conventional type which is driven through the usual 1½ volt battery cells such as used in flashlights. In the form shown, its housing is of plastic. The portion 21a thereof contains the armature and commutator while the portion 21b contains the permanent magnet field. Because of the particular shape of the motor illustrated, wheel 19 is connected to portion 21b by its stub shaft 23 inserted through block 24 which is in turn suitably connected to portion 21b as by being glued or riveted thereto. 25 Wheel 20 is connected to portion 21b through its stub shaft 25 which is similarly secured in block 26. Block 26 is in turn secured to portion 21b. Stub shafts 23 and 25 jointly constitute, in effect, the front axle and they are discontinuous only between them. Wheels 19 and 20 are freely rotatable on such stub shafts or front axle.

30 Shaft 29 of the motor may have applied thereto a collar 30 and a rubber sleeve 31 which serves as friction pulley for the belt 32. Belt 32 may advantageously take the form of an ordinary rubber band which is connected between sleeve 31 and pulley 33 connected to wheel 20. The normal size of rubber belt 32 is such that it is maintained in stretched condition between pulleys 31 and 33. Pulley 33 may, in actual practice, take the form of a simple plastic disc which is beveled inwardly as illustrated in Fig. 5, so that the rubber belt 32 rests between the pulley 33 and the wheel 20. It is firmly connected to wheel 20 by having an inner ledge thereof clamped in the metal, rivet-type hub 35. It may alternatively be adhesively secured to the wheel 20, if desired, or may be integral therewith.

35 The commutator of the motor has the usual

brushes, not shown, which have their terminals in motor housing portion 21a. To these terminals are connected wires 36 and 37 which may be in the form of a two-wire conductor. Wires 36 and 37 may be approximately 6 or more feet long so as to permit operation of the vehicle while the operator is standing or walking. Wires 36 and 37 are provided with suitable insulation, and in order to mechanically secure them, a ledge 38 is provided around which they may be coiled as illustrated in Fig. 2. The wires are connected at their remote end to a double pole, double throw switch 39 which is in turn connected to the battery source of power 40, as illustrated in Fig. 3.

Switch 39 comprises a pair of poles 41 and an opposing pair of poles 42. Arm 43 may effect contact with the poles 41 or 42 or may have a neutral position wherein the battery is cut off from the motor. Battery 40 may take the form of two series disposed 1½ volt cells enclosed in a plastic case 44 which is conveniently held in the hand while the button or arm 43 is actuated by the thumb in the operation of the vehicle.

Plate 18 is formed with side cut-outs 45 and 45a to accommodate the movement of wheels 19 and 20. The underside of plate 18 has formed thereon the projections 46 and 47 which determine the limits of swing of the front axle and thus determine the steering of the vehicle. As will be hereinafter explained, projection 46 dictates the leftward bias of the vehicle in its forward motion while projection 47 dictates the rightward steering during forward motion and the extent of the circular action in the rearward movement of the vehicle.

The operation of the vehicle in the form shown is as follows:

When arm 43 is snapped into the position where it connects the terminals 41, a circuit is formed with the armature of motor 21 which operates it in a forward direction. Inasmuch as the driving power is only applied to wheel 20 thereby producing a differential actuation of the front wheels, wheel 20 will be initially urged forward so as to swing the front wheel structure to the left. Such swinging is stopped when the front wheel structure strikes projection 46. Projection 46 is so placed that the front wheel structure can only swing slightly to the left. The driving power then drives the vehicle forwardly while it is slightly swung toward the left. It can be seen, therefore, that by pivoting the front wheel structure at point 22 and by applying driving power to one of the wheels only, steering is automatically effected through the action of the driving motor alone.

The construction as above described permits a vehicle to proceed, in effect, to a point which is in a rightward direction. This is accomplished through the positioning of projection 47. When driving power is initially applied, it will bias the front axle slightly to the left while driving it forward. If the driving power is then cut off, the wheel 19 continues to turn through the inertia of the vehicle, but the wheel 20 is restrained because the motor acts as a brake thereon. Accordingly, each time that the vehicle is stopped in its forward motion, it will turn sharply to the right. In order to permit such sharp turn, the projection 47 is effectively disposed or positioned so as to permit a considerable swing or tilt of the front axle as illustrated in the broken lines of Fig. 3. Referring to Fig. 6, if the vehicle started at point X, it can proceed to point Y which is to the right thereof by being started and stopped three

times, the lines 50, 51 and 52 representing those periods when the vehicle is driven forwardly while the lines 53, 54 and 55 represent those periods when the vehicle is stopped whereby it coasts sharply to the right. Thus can be seen that both left and right steering are provided by the simple expedients illustrated so that the vehicle can be guided substantially to any desired point.

10 The vehicle is also designed to travel rearwardly in a circle which is much sharper than the front drive to the left. An important aspect thereof is that the operator may substantially stand in one place while the vehicle runs around him. Of course, he may turn with the vehicle to avoid being tangled in the wires.

15 In order to effect the reverse drive, the arm 33 is snapped so as to connect the terminals 42. Wheel 20 will be initially pulled back so as to tilt the front axle to an extent which is limited by projection 47. The vehicle will then travel rearwardly in a circle which has a high radius of curvature as determined by the pronounced tilt of the front axle. It will be understood that the 20 bridging of either terminals 41 or 42 reverses the 25 polarity of current to the motor and thus reverses its direction.

20 The toy vehicle which has been above described is steerable in both directions without any specific 30 steering mechanism, but the steering function is quite limited in extent and variety. Accordingly, in Fig. 7 is illustrated a modified embodiment which may be completely steered in any direction.

25 In Fig. 7 are illustrated those parts of the modified embodiment which may differ from those of the first described embodiment. Wheels 60 and 61 similarly float or are freely rotatable on the front axle which is effectively pivoted at 62 for the required swinging action above described. Driving power is, however, applied selectively or jointly to both wheels. By regulating the extent of 30 driving power applied to either wheel, one wheel may be driven at a faster rate than the other so that the effect thereof is to somewhat simulate the action of the first embodiment where the driving power is confined to but one wheel. It will be recognized that by applying more power to wheel 60, for example, than to wheel 61, wheel 60 will be initially driven forward in the same 35 manner as was wheel 20 so as to cause the vehicle to be steered while driven.

40 Motor 63 applies driving power to wheel 60 while motor 64 serves wheel 61. Wires 65 and 66 are connected to respective brushes of the motors 45 and are also connected to the ends of a rotary potentiometer winding 67. Since the potential of the battery may be in the order of 3 volts, it has been found at a ¼ ohm resistance is satisfactory for winding 67. The movable arm 68 of the 50 potentiometer serves to differentially apply the electric current to either of the motors in a proportion which depends upon the setting of the movable arm. Thus, if it is swung to the extreme left, motor 64 will be furnished with most of the current, while motor 63 will be furnished with proportionately less current. The reverse is true when arm 68 is swung to the right as viewed in this figure. Intermediate positions will produce corresponding results and the vehicle may therefore be steered in either direction with precision 55 while being driven either backward or forward.

60 In order to simulate the action of a conventional automobile, a wheel 69 is connected to and above movable arm 68. It will be evident that the rotation of wheel 69 will perform the desired steer-

ing. In actual practice, the battery will be housed in the casing 44 and both the switch and the potentiometer steering control will be disposed on such casing.

What is claimed is:

1. An elongated toy vehicle comprising pairs of front and rear wheels, one of said pairs of wheels being freely swingable in a horizontal plane and relative to the longitudinal axis of the vehicle so as to steer the vehicle, an electric motor, the shaft of which is connected to one wheel only of said swingable pair of wheels so as to drive the said one wheel, the other wheel thereof being freely rotatable pursuant to the travel of the vehicle so as to produce a differential actuation of the respective wheels of said swingable wheels and thereby initially effect a swing of said swingable wheels when the motor is energized and stops positioned so as to intercept and limit the free swing of said swingable wheels and thus determine the steering angle at all times when the vehicle is being driven either forwardly or rearwardly.

2. A toy vehicle according to claim 1 and wherein said stops comprise two projections for respectively intercepting, limiting and thus determining the steering angle of said pair of swingable wheels in the forward and reverse directions, the projection intercepting free swinging in the forward direction being closer to said pair of swingable wheels than the other projection so as to produce forward travel with a substantially lesser degree of steering than in reverse travel.

3. A toy vehicle comprising a pair of wheels across one end of the vehicle, said pair of wheels being freely swingable in a horizontal plane and relative to the longitudinal axis of the vehicle so as to steer the vehicle, wheel means for the other end, an electric motor connected to one of said pair of wheels so as to drive the same and propel the vehicle, the other wheel rotating solely

through the said propulsion so as to produce a differential actuation of the respective wheels of said pair of wheels and thereby initially effect a swing of said pair of wheels when the motor is energized, and a stop positioned adjacent said swingable pair of wheels so as to intercept and limit the free swing of said pair of wheels and thus determine the steering angle at all times when the said pair of wheels has been swung in the direction of said stop and is being driven in said direction.

5 4. A toy vehicle according to claim 3 and including a second stop for determining opposite direction, said electric motor being reversible, the 10 respective stops being at opposite points relative to said pair of wheels and positioned so as to respectively intercept and limit free swing thereof each time the motor is initially energized in either 15 direction of rotation, said second stop being spaced at a different horizontal distance from said pair of wheels than said first stop so as to provide different angles of steering in the forward and reverse directions.
